UNITED STATES PATENT OFFICE.

CARL E. L. LIPMAN, OF BELOIT, WISCONSIN.

REFRIGERATING APPARATUS.

Original application filed March 6, 1926, Serial No. 92,704. Divided and this application filed August 5, 1927. Serial No. 210,943.

This application is a divisional application of my copending application Ser. No. 92,704, filed March 6, 1926.

This invention relates in general to 5 mechanical refrigerating apparatus and while the principles thereof may be utilized in apparatus of various sizes and characters designed for many purposes my invention particularly is adapted for small refrigerating installations adapted to be used in homes and commonly known as household refrigerators.

The demand for household refrigerators for use in houses and apartments is rapidly 15 increasing, but one of the deterrent factors of the household refrigerator business has been the servicing expense. Dealers in household refrigerators have been obliged to maintain a service department consisting 20 of highly trained and skilled men capable of not only repairing refrigerating apparatus but of diagnosing the troubles which arise in connection with apparatus of this character. This servicing expense must 25 eventually be borne by the householder either in the increased price which he initially pays for his refrigerating apparatus or as an upkeep expense during the operation of the apparatus.

30 One of the primary purposes of my present invention is to eliminate the burdensome servicing cost which has heretofore been an inherent factor of household refrigeration and to relieve the dealer entirely of 35 the necessity of maintaining the service department or even men skilled in the art of refrigeration.

With this end in view my invention contemplates the provision of a refrigerating 40 unit which is completely assembled at the factory and may be shipped and handled as any other commodity or article of merchandise might be, this unit as a whole being adapted to be inserted in a refrigerator 45 cabinet and be put in service by simply connecting the cabinet up with an electric circuit. Should the apparatus fail to work for any reason or should it become worn so as to require repairs the householder needs 50 simply to withdraw the unit from his cabinet and exchange it with his dealer for another unit which may be slipped into the cabinet to replace the faulty one. This exchange requires no skilled labor whatsoever and can be effected in a few moments.

The dealer, instead of attempting to diagnose the trouble with the defective unit and repair it, simply ships the unit intact back to the factory where the repairs can be quickly and economically made by skilled 60 repairmen. The unit may then be reshipped to the same or another dealer to be reinstalled when occasion requires. The dealer, therefore, by keeping on hand a few extra units is always in a position to keep his customers supplied with refrigeration and is relieved of the necessity of a service department or of skilled labor, thereby greatly reducing not only the initial cost of a refrigerator installation but also the maintenance cost. 65

70 While my invention is not restricted to any particular type of refrigerating apparatus and contemplates the employment of apparatus of the compressor type, the absorption type or the adsorption type, I have for purposes of illustration merely shown and described herein a simple system of the compressor type as illustrative of the general principles of my invention. 75

80 My invention and many of its inherent advantages in addition to those above mentioned should be readily appreciated as the same becomes better understood by reference to the following description when considered with the accompanying drawings. 85

Referring to the drawings:

Fig. 1 is a front elevation of a refrigerating cabinet equipped with my invention, a portion of the cabinet being removed to 90 more clearly illustrate the inclosed apparatus,

Fig. 2 is a sectional view taken substantially on the line 2-2 of Fig. 1,

Fig. 3 is a perspective view of my novel 95 unit removed from the cabinet,

Fig. 4 is a front elevation of a modified type of cabinet, and

Fig. 5 is a sectional view taken on the line 5-5 of Fig. 4. 100

Referring now to the drawings more in detail reference character 5 indicates generally a refrigerating cabinet of any approved type preferably including in its construction, as is customary, suitable heat insulating material which contributes to the efficiency of the cabinet. 105

The cabinet may be equipped with the usual shelves and partitions to facilitate the storage of perishable products and in the 110

form herein illustrated it is provided in its upper portion with horizontally extending cleats or members 6 forming guide-ways 7 for the reception of a support or partition wall 8 including in its construction suitable heat insulating material. While in the particular cabinet disclosed the guide-ways are horizontally disposed to support the partition in a horizontal position, it should be understood that the guide-ways may be positioned to receive and sustain the partition wall in a vertical position without in any way departing from the spirit of my invention.

15 The partition or supporting wall 8 constitutes one of the elements of my refrigerating unit which is removable as a whole and intact from the cabinet and replaceable by a similar unit when desired. The unit 20 comprises, therefore, this supporting wall and a complete refrigerating system, preferably of the closed refrigerant circuit type carried by and removable with the wall. This wall when in place divides the cabinet 25 into two compartments, one of which indicated by reference character 9 is the food compartment or chamber and the other of which indicated by 11 constitutes what may be termed the compressing and condensing chamber. It should be understood by the term compressing and condensing I do not intend to limit the apparatus employed to compression type, but that the term compressing and condensing is employed generically to include both the absorption and adsorption type, a still, or any other apparatus which serves to generate the refrigerating action through the intermediary of a suitable refrigerating medium.

40 The refrigerating system, as previously stated, is carried by and removable with the wall 8 and the system shown herein for illustrative purposes merely comprises a motor and compressor 12 and a condenser 13 constituting broadly the apparatus included in the high pressure or condensing side of the system and an expansion valve or float chamber 14 through which the refrigerant is admitted to the expansion chamber 15 if the apparatus be of the flooded type or to coils if the system be of the expansion valve type. The refrigerating element 15, either a receptacle or coils as previously stated, is connected with the compressor 12 through the return line 16, as is customary. The refrigerating element 15 surrounds suitable compartments 17 adapted to receive the ice trays 18 in which ice is produced in a well known manner. If desired these compartments may be surrounded or immersed in brine or like material.

It will be apparent that the apparatus comprising the high pressure or condensing side of the system is located on one side of the supporting wall 8 in the compartment

11, while the refrigerating element constituting the low pressure or evaporating side of the apparatus is located on the opposite side of the supporting wall 8 and in communication with the perishable product storage chamber of the cabinet where refrigeration is desired. To facilitate air circulation in the storage chamber, baffles 19 may be arranged adjacent the refrigerating element as illustrated in the drawings, these baffles being carried preferably by the cabinet or by the supporting wall 8 if found more expedient.

The refrigerating system may be either water cooled or air cooled and if water cooled a slip connection may be provided through which the cooling apparatus may be connected with the water system by the inserting of the removable unit into the cabinet. In the present instance, I have illustrated an air cooled system and for the purpose of obtaining the requisite cooling I have mounted upon the wall 8 near one side thereof and within the chamber 11 an electric or blower fan 21 which blows air through the condensing coils 13 and around the compressor 12, which for purposes of efficiency may be equipped with radiating fins 22. The side walls of the cabinet are provided with air inlet and outlet openings 90 preferably equipped with louvers. A thermostat 24 of usual construction may be located at any desirable point in the storage chamber for controlling the operation of the refrigerating apparatus.

In the electrically operated air cooled system herein illustrated wherein the fan and the compressor are electrically driven, connection with the electric circuit is automatically established when the supporting wall 8 is slid into position. To accomplish this result a slip connection 25 comprising a part mounted on the rear wall of the chamber 11 and a part mounted on the upper face of the supporting wall 8 is employed and the cabinet is wired from this connection to an outside socket 26 which may be readily connected with an electric light circuit through a plug and socket connection. It will be noted that the electrical motor 21 for operating the fan is entirely independent of the motor 12 for operating the compressor. While I have disclosed the separate motors for operating the fan and compressor, respectively, as being connected in series, yet in actual practice it is probably preferable to connect the same in parallel.

It will be apparent from the foregoing that I have provided a refrigerating unit which is readily insertable into and removable from a cabinet as a whole without disconnecting or disturbing the arrangement of the various elements of the unit. These units may be assembled at the factory and shipped intact to the dealer who handles

them as any other commodity without attention to repairs or service. The user, if the unit fails, simply removes it from the cabinet and replaces it with another unit which he obtains from his dealer. The defective unit is returned to the factory where it is quickly repaired by those skilled in this art and it may then be reinstalled for further use.

While the partition wall 8 may alone be relied upon to seal the generator chamber 11 from the storage chamber, I prefer, for purposes of efficiency, to make this seal more effective by providing an auxiliary sealing wall 27 which may be and preferably is a part of the unit as a whole. This wall incorporating in its construction heat insulating material, is secured to the front edge of the supporting wall 8 and when the unit is positioned within the cabinet the margins of this wall abut against cleats 28 arranged within the cabinet, as shown in the drawings. When the unit is in place, therefore, the generating chamber 11 is effectually sealed from the storage chamber 9 and the opening of the cabinet door 29 does not permit the flow of warm air from the generating chamber downwardly into the storage chamber to reduce the efficiency of the installation. Preferably also, this wall extends downwardly to a point below the refrigerating element 15 so that warm air from the outside does not strike this element when the cabinet door is opened.

While in Figs. 1 and 2, I have shown a door 29 which completely closes the refrigerating unit and the storage compartment of the refrigerator, I do not limit myself to this particular mode of housing the said parts, and in this connection I refer to Figs. 4 and 5 wherein I have shown the storage compartment sealed with a door 31 having the usual hinges 32 and latch 33, and this door has a portion which overlaps the front wall or partition of the refrigerator to effectually seal the said compartment. The refrigerating unit and its parts which have been described are mounted in precisely the same manner as those shown in Figs. 1 and 2, except that the auxiliary sealing wall 27 is made to fit flush with the front wall or partition of the refrigerator proper and is provided on the outer side thereof with a member 34 which has flanges 35 for fitting over and around the opening into which the said sealing wall is adapted to fit. In such cases, the small ice tray compartments 18 will be provided with a door 36 which is hinged as at 37 to cover the said compartment, and this door is provided with the usual heat insulating material which can be observed at the point 38, in Fig. 5. By the use of this construction, the large door covering the entire refrigerator is eliminated and one or more small doors may be used for gaining access to the food compartment,

while the refrigerating unit may be drawn forward horizontally by grasping the handles 39 in the same manner as the construction shown in Figs. 1 and 2, except that the door 29 will be eliminated and the entire cabinet 70 will not be opened to the atmosphere when it is desired to gain access to any particular part of the interior.

The construction, operation, and many of the inherent advantages of my invention should be apparent from the foregoing without further description and while I have shown and described a preferred embodiment, obviously the details of construction, arrangement of walls and type of apparatus 80 employed may all be varied within wide limits without departing from the essence of my invention as defined in the following claims.

What I claim is:

1. In a refrigerating apparatus the combination of a cabinet, a partition wall of heat insulating material removably disposed in said cabinet, a refrigerating device carried by and removable with said wall, the apparatus comprising the high pressure side of the device being disposed at one side of said wall and the apparatus comprising the low pressure side of the device being disposed at the opposite side of said wall, and an electric circuit connected with the apparatus for driving the same including a connection closed by the insertion of said removable wall into place and broken by the removal of said wall.

2. The combination with a cabinet having an opening therein, a refrigerating apparatus insertable and removable into and from said cabinet through the said opening therein, said refrigerating apparatus comprising a compressor, a condenser coil operatively associated with said compressor, a compressor motor, means for air-cooling said condenser and compressor, said means including a fan, an electric motor for said fan, a thermostat electrically connected with both the fan and compressor motors respectively, whereby said motors are operated concurrently, electrical circuits connected with said motors including a connection with said cabinet which is automatically broken by the removal of said apparatus from said cabinet.

3. The combination with a refrigerating cabinet, a unit comprising a support, a compressor, a compressor motor mounted on said support, means for hermetically sealing the said motor and compressor, a condenser mounted on said support means for air cooling said condenser comprising an electric fan and a motor therefor mounted on said support, an electrical circuit connected with said motors for actuating said motors concurrently, said support and refrigerating apparatus thereon being removable as a unit

- 4
- from the cabinet in which the same are adapted to be placed, said circuits including a connection that is broken by the removal of the apparatus from the cabinet.
- 5 4. The combination with a cabinet having an opening therein, a refrigerating unit comprising a compressor and an electric motor for driving said compressor, an electric circuit for said motor including a connection automatically closed upon the insertion of said unit through the opening into said cabinet and broken upon the removal of the unit from the cabinet.
- 10 5. The combination with a refrigerating cabinet, of a mechanical refrigerating apparatus including a compressor associated with the cabinet, said refrigerating apparatus being removable from the cabinet as a unit without disturbing the relation of the
- 20 20 parts of the apparatus, electrical means for actuating said compressor, an electrical circuit connected with the means for actuating the compressor and including a knife switch connection between the unit and cabinet to
- 25 automatically break the circuit upon the removal of the unit from the cabinet.
6. The combination with a refrigerating cabinet, of an opening therein, a mechanical refrigerating apparatus including a compressor horizontally insertable and removable, as a unit, into said cabinet through said opening, electrical means for actuating said compressor, a circuit for supplying electrical energy to the said electrical means and
- 30 35 including a connection serving to automatically break the circuit upon the removal of the unit from the cabinet.
7. The combination with a refrigerating cabinet, of a refrigerating unit comprising a support and mechanical refrigerating apparatus including a compressor carried by said support and removable therewith as a unit from the cabinet without disturbing the refrigerating apparatus, electrical means for driving said compressor, a circuit making and breaking device automatically disconnectable upon the removal of the unit from the cabinet, said circuit making and breaking device comprising contacts fixedly secured to the interior of the cabinet, and contacts carried by the support of said unit, said contacts being brought into operative relationship when the unit is in its inserted position.
8. The combination with a refrigerating cabinet, having an opening therein, a unitary assemblage of refrigerating apparatus including a compressor bodily insertable and removable into and from said cabinet through said opening, electrical means for driving the compressor, an electrical circuit for supplying current to operate the apparatus, including a switch connection for automatically breaking the circuit upon the removal of the unitary assemblage from the cabinet.

In witness of the foregoing I affix my signature.

CARL E. L. LIPMAN.
